(57) **CLAIM**

The ornamental design for a set of multi-device faceplates, as shown and described.

DESCRIPTION

FIG. 1 is a front perspective view of the set of multi-device faceplates; and,

FIG. 2 is a front elevation view thereof.

The FIGUREs are shown with the devices stacked together so that each individual faceplate has a depiction that corresponds to depictions in adjacent faceplates in order to display a consolidated image across all of the faceplates. The broken lines are shown in the views for illustrative purposes only and form no part of the claimed design.
